LOCOMOTIVE FRONT END

Leslie R. Pyle, Chicago, Ill., assignor to Locomotive Firebox Company, Chicago, Ill., a corporation of Delaware

Application December 11, 1944, Serial No. 567,708

7 Claims. (Cl. 230—97)

This invention relates to improvements in locomotive front ends and it consists of the matters hereinafter described and more particularly pointed out in the appended claims. The invention is more especially concerned with front ends that include spark arresting vanes arranged to impart a whirling action to the products of combustion entering the front end for entrainment up the stack under the action of the exhaust steam discharged by a nozzle arranged in line 10 with said stack.

One of the objects of the invention is to provide a vane arrangement for the front end, which avoids the necessity of one or more bottom baffle plates, which is of a more simple construction for 15 low cost production and which may be readily installed in the front end.

Another object of the invention is to provide a vane arrangement of this kind which is more free of such obstructions that promote the accumulation of the cinders and the like in the bottom of the smoke box shell and whereby the shell remains in a cleaner condition for longer periods of times between service operations.

A further object of the invention is to provide a vane arrangement for the front end which may be more readily disassembled and removed from the front end to permit better access to superheater and like parts in the front end, as well as to the ends of the flues in the flue sheet at the rear end of the smoke box shell.

The above mentioned objects of the invention, as well as others, together with the advantages thereof, will more fully appear as the specification proceeds.

In the drawings:

Fig. 1 is a longitudinal vertical sectional view through a locomotive front end embodying the preferred form of the invention.

Fig. 2 is a horizontal detail sectional view through a part of the front end structure shown in Fig. 1 on the line 2—2 thereof and on a scale enlarged thereover.

Fig. 3 is a view similar to Fig. 2 as taken on the line 3—3 of Fig. 1.

Fig. 4 is a transverse vertical sectional view through the front end structure shown in Fig. 1 as taken on the line 4—4 thereof and on the scale of Figs. 2 and 3.

Figs. 5 and 6 are detail vertical sectional views through parts of the front end structure appearing in Fig. 2 as taken on the lines 5—5 and 6—6 respectively on Fig. 2 and on a scale enlarged thereover.

Fig. 7 is a perspective view of one of the plate

parts of the spark arrester embodied in the improved front end.

Fig. 8 is a detail vertical sectional view through a part of the spark arrester of the front end as taken on the line 8—8 and on a scale enlarged over that of Fig. 4.

Fig. 9 is a horizontal detail sectional view through parts shown in Fig. 8 as taken on the line 9—9 thereof.

Fig. 10 is a detail vertical sectional view on the line 10—10 of Fig. 2 and on a scale enlarged thereover.

Fig. 11 is a detail horizontal sectional view as taken on the line 11—11 of Fig. 10.

Referring now in detail to that embodiment of the invention illustrated in the drawings, 10 indicates as a whole the tubular body of a locomotive smoke box shell which is connected at its rear end to the front end of the boiler shell 11 in a conventional manner. The interior of the smoke box shell is separated from the interior of the boiler shell by a flue sheet 12. Flues 13 open through the sheet 12 so as to discharge products of combustion into the smoke box shell. In Fig. 1 only one of said flues is shown and this is in dotted lines. 14 indicates the front of the smoke box shell which is provided with the usual door. At the bottom of the smoke box shell is a floor plate 15.

16 indicates the flanged base for the smoke stack. Said base is directly attached to the top of the body 10 of the smoke box shell about an opening 17 therein. The smoke stack has a tubular extension portion or lift pipe 18 fixed to its bottom end and said portion depends into the interior of the body of the smoke box shell as best appears in Fig. 1.

The exhaust pipe which is indicated at 19 rises from the bottom of the body of the smoke box shell in axial alignment with the tubular portion of the stack. Said pipe is provided at the top with an exhaust nozzle or tip 20 of any approved kind.

In the body 10 of the smoke box shell is located 45 a spark arrester of the so-called circumferentially open, centrifugal separator type which is indicated as a whole in Figs. 1 and 4 at 21. Said arrester, which is cylindrical in shape, has its axis arranged in alignment with the axes of the portion 18 of the stack and the nozzle or tip 20 of the pipe 19 respectively.

The spark arrester includes a circular top plate 22 disposed substantially in the plane of the bottom end of the stack portion and which in turn 55 is disposed substantially in the plane of the longi-

tudinal axis of the smoke box shell. Said top plate, which extends radially outward from the stack portion 18, is made in two semicircular front and rear parts 23 and 24 respectively, as best shown in Fig. 2, one of said plate parts appearing in perspective in Fig. 7. Welded to one end of each semicircular part is a strip 25 that overlaps the marginal part of the other end of each part and is operatively secured thereto as by bolts 26 as best appears in Fig. 1. Each plate part 23-24 has a semi-circular cutout to embrace a part of the stack portion 18. Following about each cutout is a semicircular attaching member or flange 27 having straight ends 28. The central bottom portion of each member 27 is welded to the associated plate part as at 29 so that the ends of said member will have a springy action. Said ends of said members 27-27 are operatively drawn together by bolts and associated nuts 30. When the nuts are drawn up tight, the ends of the members 27-27 are drawn together with a clamping grip action upon the stack portion. By removing the bolts 30 and 26-26 it is obvious that the plate parts 23-24 may be separated from each other for removal and replacement.

Associated with the front and rear plate parts 23-24 are sets of front and rear perpendicular deflector plates or vanes 31 and 32 respectively, arranged to occupy a circular area or path about the peripheral margins of the top plate 22 as a whole. The deflector plates are disposed tangentially with respect to the axis of the stack portion and are operatively attached at their upper ends to the respective plate parts 23-24 and at the lower ends to the bottom of the body of the shell 10 or to the floor plate 15 thereon.

The lower end portion of each deflector plate 31-32 is cut to shape to correspond to the contour of that part of the floor plate it is to occupy and on said floor plate and arranged in the pattern in which the deflector plates are disposed are upstanding flange like parts 33, one for each deflector plate. Said lower end portion of each plate engages flatwise against its own flange like part and is detachably secured thereto by a bolt and associated nut 34, the bolt passing through aligned openings in said plate and part 33 respectively.

Depending from the underside of both plate parts 23-24 are flange-like parts 23a and 24a respectively arranged in the pattern in which the deflector plates 31-32 are disposed. The upper end of the plates 24 are secured to the flanges 24a by bolts and associated nuts 35. Extending through each flange part 23a is a key bolt 36. The headed end of each bolt is secured against loss from the associated plate part 23 by a chain 37. The other end of said key bolt has a longitudinal slot therein to receive a wedge 38 whereby the upper end of each deflector plate 31 is detachably secured to the plate part 23a.

The plates or vanes 31-32, which are constituted by flat plates, are each provided on opposite sides toward but spaced different distances from the outer end thereof with right angled deflector wings or baffles 31a-32a respectively. The deflector wings 32a extend the full height of the associated deflector plate 32 while the deflector wings 31a extend only part way up from the bottom of each plate 31.

While the deflector plates 31-32 have been mentioned as plain flat plates and straight transversely, they may be made to have some curvature transversely. As before mentioned, while they are disposed tangentially with respect to

the axis of the stack portion 18, they also extend inwardly from the outer circle of the plate parts 23-24 to terminate short of the stack portion 18.

Within the upper portion of the interior of the arrester 21 is located another set of deflector vanes 40 of an auxiliary character and which are supported from the plate parts 23-24. The vanes 40, which are also disposed tangentially of the axis of the stacks portion, extend in a direction opposite that of the vanes 31-32. The vanes 40 are secured in arcuately spaced relation by top and bottom end rings 41 and 42 of a diameter approximating that of the bottom end of the stack portion 18. The upper ring is provided with laterally extending ears 43 and bolts 44 pass through said ears and portions of the plate parts 23 and 24 thereabove. Nuts are provided for said bolts and when said nuts are drawn up tight, this clamps the deflector vanes in place with the upper ring in engagement with the bottom edge of the stack portion 18.

With the arrangement described, it is to be noted from Figs. 1 and 4 that room or space is present at opposite sides of the arrester for the passage of steam pipes 45 which lead to the cylinders of the locomotive. These pipes have a flanged upper end connection with superheater headers 46 located in the upper rear portion of the smoke box shell. Said pipes and headers, as well as superheater tubes 47 best appear in dotted lines in said Figs. 1 and 4.

In the operation of the locomotive of which the described construction forms a part, the products of combustion enter the interior of the body of the smoke box shell from the flues under the draft action induced by the exhaust steam jet discharged by the nozzle 20. Such products of combustion vary in size, some being relatively fine and light in weight and others being relatively heavy and in the form of cinders, some of which may be glowing and in the form of sparks. As the products of combustion enter the body of the smoke box shell, they travel in a substantially horizontal plane toward the arrester 21. In the discharge of exhaust steam from the nozzle up the stack portion 18, a subatmospheric condition is established so that the products of combustion pass through the passages between the vanes 31-32 to enter the arrester 21 and be entrained for passage up and out through the stack. In this movement of said products of combustion, certain particles thereof impinge the baffle plates 31a and 32a and are broken up into smaller pieces for a better extinguishment thereof. Furthermore, in said movement the vanes impart a swirling motion of said products of combustion in one direction. However, as the vanes 40 are directionally opposed to the plates or vanes 31-32, said vanes 40 tend to counteract said whirling action so that the particles of said products of combustion are directed back toward and into the blast for entrainment out through the stack.

It is to be noted that the arrester is open from the plate 22 to the bottom of the smoke box shell or the floor plate therein. Therefore such particles of the products of combustion as may not directly enter the arrester by means of the passageways between the plates or vanes 31-32 are kept in a state of turbulence in the bottom of the shell within the area of the arrester. Such particles in their movement, eventually are caught in the blast produced by the nozzle and pass up and are discharged out through the

stack. Therefore the front end remains in a clean condition.

Should it be necessary to service parts in the body of the smoke box shell, the arrester may be readily disassembled and removed therefrom out through the front end of the shell. Thus free access is had to superheater headers, tubes, steam pipes and the flue sheet for whatever service is necessary. Thereafter the arrester may be reassembled in operative position in the smoke box shell.

While in describing the invention I have referred in detail to the form, arrangement and construction of the parts involved, the same is to be considered only in the illustrative sense so that I do not wish to be limited thereto except as may be specifically set forth in the appended claims.

I claim as my invention:

1. In combination with the smoke box shell of a locomotive boiler, a smoke stack having a bottom end portion disposed in said shell, a nozzle at the bottom of said shell arranged to discharge exhaust steam into said stack portion, a plurality of vanes arranged in a circular path about said stack portion and extending downwardly therefrom toward the bottom portion of said shell, means for attaching the lower end of said vanes to said bottom of said shell, and means surrounding a part of said stack portion and extending outwardly therefrom and to which the upper ends of said vanes are attached.

2. In combination with the smoke box shell of a locomotive boiler, a smoke stack having a bottom end portion disposed in said shell, a nozzle at the bottom of said shell arranged to discharge exhaust steam into said stack portion, a plurality of vanes arranged in a circular path about said stack portion and extending downwardly therefrom toward the bottom portion of said shell, a plurality of members projecting upwardly from said bottom of the shell, one for and attached to the lower end of each vane, and means surrounding a part of said stack portion and extending outwardly therefrom and to which the upper ends of said vanes are attached.

3. In combination with the smoke box shell of a locomotive boiler, a smoke stack having a bottom end portion disposed in said shell, a nozzle at the bottom of said shell arranged to discharge exhaust steam into said stack portion, a plurality of vanes arranged in a circular path about said stack portion and extending downwardly therefrom toward the bottom portion of said shell, means for attaching the lower ends of said vanes to said bottom of said shell, means surrounding a part of said stack portion and extending outwardly therefrom, a plurality of members depending downwardly from said means, one for the upper end of each vane, and means for attaching the upper end of each vane to an associated depending member.

4. In combination with the smoke box shell of a locomotive boiler, a smoke stack having a bottom end portion disposed in said shell, a nozzle at the bottom of said shell arranged to discharge exhaust steam into said stack portion, a plurality of vanes arranged in a circular path about said stack portion and extending downwardly therefrom toward the bottom of the shell, means for attaching the lower ends of said vanes to said bottom of said shell, means surrounding a part of said stack portion and extending outwardly

therefrom and to which the upper ends of said vanes are attached, and a split ring carried by said means and operable to have a clamping grip on said stack portion for operatively securing said means to said stack portion.

5. In combination with the smoke box shell of a locomotive boiler, a smoke stack having a bottom end portion disposed in said shell, a nozzle at the bottom of said shell arranged to discharge exhaust steam into said stack portion, a plurality of vanes arranged in a circular path about said stack portion and extending downwardly therefrom toward the bottom of the shell, means for attaching the lower ends of said vanes to said bottom of said shell, means surrounding a part of said stack portion and including a plurality of arcuate plate-like parts and which plate-like parts extend outwardly from said stack portion, means for attaching the upper end of said vanes to said plate-like parts, split ring parts carried by said plate-like parts and surrounding said stack portion, and means operatively connecting the ends of said ring parts for drawing them together in a clamping grip upon said stack portion.

6. In combination with the smoke box shell of a locomotive boiler, a smoke stack having a bottom end portion disposed in said shell, a nozzle at the bottom of said shell arranged to discharge exhaust steam into said stack portion, means surrounding the lower end of said stack portion and including a plurality of plate-like parts extending outwardly from said stack portion and having overlapping ends, a split ring part fixed to each plate-like part, said split ring parts surrounding said stack portion and being operable to clampingly grip upon said stack portion, means associated with said overlapping ends of plate-like parts for connecting them together, a plurality of vanes having their upper ends detachably secured to and depending from said plate-like parts toward the bottom end of said shell and means for operatively securing the bottom ends of said vanes in position relative to smoke box shell.

7. In combination with the smoke box shell of a locomotive boiler, a smoke stack having a bottom end portion disposed in said shell, a nozzle at the bottom of said shell arranged to discharge exhaust steam into said stack portion, means surrounding the lower end of said stack portion and including a front plate-like part and a rear plate-like part, said plate-like parts projecting outwardly from said stack portion and having overlapping ends, means for detachably connecting the overlapping ends of said plate-like parts together, means for detachably securing said plate-like parts to said stack portion, a plurality of vanes arranged in sets in a circular path about said stack portion, there being a set of each vanes associated with each plate-like part, and depending therefrom toward the bottom of the smoke box shell, means for securing the upper end of the vanes in one set to said rear plate-like part, means for securing the lower end of the vanes in said one set to said bottom of said shell, means for detachably securing the upper end of the vanes in the other set to said front plate-like part, and means for detachably securing the lower end of the vanes in said other set to said bottom of said smoke box shell.
